COMBINED PIGGY BANK AND HOLDER OR SIMILAR ARTICLE

Richard Senior and Laura C. Senior, Compton, Calif.

Application October 25, 1954, Serial No. 32,811

Term of patent 14 years

(Cl. D34—11)

FIG - 1

FIG - 3

Fig. 1 is a top plan view of a combined piggy bank and holder or similar article, showing our new design;

Fig. 2 is a side elevational view thereof; and

Fig. 3 is a perspective view thereof, to a reduced scale.

The broken line showing of oil cans or similar articles is for illustrative purposes only.

We claim:

The ornamental design for a combined piggy bank and holder or similar article, as shown and described.
